ISADORE COHEN AND ALEXANDER LANDSBERG, OF NEW YORK, N. Y.

EYELETING-MACHINE WITH AUTOMATIC FEED.

1,074,490.

Specification of Letters Patent. Patented Sept. 30, 1913.

Application filed August 22, 1912. Serial No. 716,354.

To all whom it may concern:

Be it known that we, ISADORE COHEN, a subject of the Emperor of Russia, and ALEXANDER LANDSBERG, a citizen of the United States of America, both residents of New York, county and State of New York, have invented certain new and useful Improvements in Eyeleting-Machines with Automatic Feed, of which the following is a full, 10 clear, and exact specification.

This invention has for its principal object to provide an apparatus for binding loose leaves of paper by means of eyelets and for punching the holes adapted to receive the 15 eyelets and thereafter to roll up the lower flanges of said eyelets on the undersides of the paper sheets or staples in such a manner that the paper is securely held together between the two flanges of the eyelet.

Another object of the invention is to provide a machine which by one action of the 20 plunger perforates the paper and forms the lower flange of the eyelet.

A further object of this invention is to 25 provide a machine in which the eyelets are fed through a drum into their working position above the anvil and below the punching tool in such a manner that one movement of the plunger is sufficient to bring the eyelet into its working position, to perforate 30 the paper and to roll the lower flange of the eyelet up.

A still further object of the invention is to provide an eyeleting machine, the plunger 35 of which is capable of executing downward movement to enable the punch to perforate the paper, without operating upon the eyelet which in this case is in the drum withdrawn from the anvil.

Other objects and advantages of our apparatus will become apparent from the following description and it will be understood that changes in the machine as shown and described may be made within the scope of 45 the invention without departing from the spirit thereof.

In the drawing, forming a part of this specification in which like numerals of reference indicate similar parts in the several 50 views: Figure 1 shows the machine in front view. Fig. 2 is a side view thereof showing an eyelet in position to be operated upon, and Fig. 3 is another side view showing the drum containing the eyelet withdrawn from

the punch which is in its depressed position 55 for making a hole through a staple of papers.

The machine is cheaply made of metal and of very simple construction.

It consists of a base plate 10, upon one side of which a curved arm 11 is mounted carrying at its front end a laterally disposed vertical sleeve 12, and near the same a slightly bent upright arm 13 extending above the sleeve 12. An anvil 14 is firmly 60 secured upon or preferably made of one piece with the base plate 10. Upon this anvil is firmly secured or supported upon a suitable spring 15, a boss 16 provided with a countercheck 17 for a yielding plunger 65 pin 18. Said plunger pin is mounted to slide yieldingly within the sleeve 19 in which it is loosely mounted, said sleeve being loosely guided in a central vertical opening of the sleeve 12. At the upper end of 70 said plunger sleeve 19 a vertical flange 20 is formed to receive the lower ends of two links 21, 21'. A pivotal pin 22 extends through the central part of said flange on the sleeve 19, and said links, and securing 75 pins 23 or the like pass through the outer protruding ends of said pin 22 and secure the parts in position. The upper free ends of said links 21, 21' form a bearing for the pin 24 constituting a pivotal connection for 80 the plunger bar 25 between these links, and cross pins 26 serve to secure the parts in position. The outer end of said plunger bar 85 25 is provided with a suitable handle 26^a secured to the bar in any well known manner. The bar 25 may be made of one piece of metal or may be divided intermediate its ends so as to form a joint 27 to allow a folding of the bar upon itself for packing purposes or for the purpose of preventing the 90 bar from forming an obstruction upon a desk, etc.

Near its outer end the plunger bar is provided with a suitable opening adapted to receive a small shaft 28, one end of 100 which is firmly secured in the upper end of the arm 13 by means of a nut 29, while the other end forms the pivot or journal of an arm 30, depending from said shaft 28. The bearing of said arm is mounted on said 105 shaft in such a manner that its movement is retarded by a friction washer 31, which is held against the bearing of the arm by a

screw head 32 upon the outer end of the shaft. Below its pivot the arm 30 is provided with a pin 33 and a curved pin 34 provided upon the under side of the bar 5 25 strikes during the depression of the plunger against the pin 33 thus imparting an outward movement to the arm 30. The outer end of the plunger bar is set off as shown at 35 and is provided with a hole 36 10 in which one end of a spiral spring 37 is secured, the lower end of which is secured to a pin 38 laterally projecting from the arm 11. Intermediate the hole 36 and the shaft 28 the plunger bar 25 is provided with 15 a laterally extending pin 39 adapted, when the handle 26 is raised, to impart an inward movement to said arm 30. At its lower end the arm 30 carries at an inclination to its vertical axis an eyelet guide block 40 removably secured to said arm by 20 a set screw or the like 41 said guide block being provided with a T-shaped groove 42 adapted to receive the eyelets to be used. A spring 43 has one of its ends secured to 25 the outer side of said guide block by means of a screw 44, or the like, while its other end is rectangularly bent as at 45 and embedded in a horizontal notch in the forward end of said guide block, and projecting 30 across the lower end of said T-shaped groove so as to yieldingly arrest the lowermost eyelet. It is clear that the lowermost of the eyelets within the guide block will be held by the rectangular bent portion 45 of 35 the spring 43 in position to be operated upon above the countercheck 17 and below the punch 18. A suitable paper guide 47 is adjustably secured to the base plate 10 by a set screw 48. It is clear that one or more 40 of said paper guides or gages may be employed, or a guide of larger size than the one shown may be secured in front of the anvil. The eyelets to be operated upon are inserted in a grooved rod or feeder 50, 45 adapted to be introduced above into a T-shaped groove 42.

A small projection 52 is formed approximately in the center of the outer wall of the sleeve 12 oppositely disposed to the arm 50 30, in order to limit the downward movement of said arm. Instead of the feeder 50 a chute or the like may be firmly secured to the upper edge of the guide block 40 or other similar contrivances may be 55 used to feed the eyelets into the guide block.

The operation of the machine is the following: The eyelets having been brought 60 by their own gravity and slide down into the T-shaped groove 42 of the guide block until the foremost eyelet strikes the end 45 of spring 43, assuming the position of Fig. 2 ready to be operated upon by the punch 65 which at the depression of the plunger bar

will perforate the paper and roll up the lower flange of the eyelet upon the underside thereof thus securely binding the sheets together, or if one sheet is used only making a hole in the paper, the edge of which is 70 lined by a metal ring.

If it is desired for any purpose, such, for instance, as when a very thick staple of papers is to be operated upon, to punch the holes without operating upon the eyelets, the plunger bar is pressed only part way down, carrying the pin 39 away from the arm 30, when the said arm may be manually swung outward on its pivot to substantially the position shown in Fig. 3 75 80 whereby the eyelet held in the inner end of the guide block will be removed out of the path of the punch. The arm 30 will be held in this position by means of the friction washer 31 and screw head 32, and the plunger bar may be reciprocated to cause the punch to operate, without acting upon the eyelets, provided said plunger bar is not forcibly raised high enough to cause the pin 39 to press the arm 30 inward far enough to move the forward end of the guide block 40 with an eyelet therein into the path of the punch. The friction of the washer 31 on the arm 30 is sufficient to prevent the spring 37, without manual assistance, from causing the pin 39 on the plunger bar to press the arm 30 inward to the position of Fig. 1, so that the parts will be maintained in the punching positions so long as the plunger bar is not raised high enough to cause said pin 39 to press the arm 30 inward to the position of Fig. 1. 90 95 100

To resume the operation of both punching and eyeleting, it is only necessary to raise the plunger bar to its highest position, as shown in Fig. 1, which will bring the eyelet in the inner end of the guide block into the path of the punch to be operated upon thereby.

As the plunger bar is pressed downward 110 to near the end of its stroke, the yielding pin 18 enters the eyelet in advance of the punch reaching it. At this point the curved pin 34 presses against the pin 33 and forces the arm 30 outward, removing the inner end of the guide block out of the path of the punch 19 which is continuing downward to punch the hole and operate upon the eyelet upon the yielding pin 18. Another eyelet will now slide down to position in the inner 115 120 125 end of the guide block.

Changes may be made in the general arrangement and dimensions of the parts without departing from the spirit of the invention.

Different sizes and styles of eyelets may be used in this machine, by simply changing the feeder and guide block for others of proper form, which changes will not depart from the spirit and scope of the invention. 130

Having thus described our invention, what we claim is:

1. An eyeleting machine of the character described, comprising, in combination, a punch, an exchangeable eyelet feeding receptacle, a vertical swinging arm carrying said receptacle at its lower end, means adapted to move said arm into feeding position when the punch is moved upward, means operating simultaneously with the eyeleting operation to move the arm out of feeding position, and a frictional pivotal support for the vertical swinging arm to hold said feeding receptacle out of feeding position during punching operation.
2. An eyeleting machine comprising a base, a standard on one side of said base, a laterally disposed vertical sleeve integral with said standard, a punch slideable in said sleeve, a vertical extension on said standard carrying a horizontal bearing sleeve, a horizontal pin in said sleeve, a plunger bar pivotally mounted upon said horizontal pin, means for connecting said plunger bar intermediate its end with the punch, a vertically depending arm frictionally pivoted on said horizontal pin, an eyelet guide block removably secured to the lower end of said arm, and means for moving the vertical arm on its pivot during the upward and downward movement of the plunger bar.
3. In an eyeleting machine of the character described, a punch, a handle lever for reciprocating the punch, a guide and block for feeding the eyelets to position to be operated upon, connections between the eyelet feeding devices and the lever for moving the

feeding means into and out of operative position, and a frictional support for the eyelet feeding means for holding said feeding means out of feeding position during a limited portion of the reciprocation of the punch.

4. In an eyeleting machine, in combination, a base, an arm mounted thereon, a vertical sleeve carried thereby, an extension integral with said arm, a horizontal sleeve carried at the top of said extension, a horizontal bolt in said horizontal sleeve, a plunger bar pivotally mounted on said bolt, an arm depending vertically from said bolt, friction means for securing said arm in various positions, a punch in the vertical sleeve, a link connecting the punch with the plunger bar, an extension on the plunger bar beyond its pivot, a pin projecting laterally therefrom to connect with and move the vertical depending arm inward when the plunger bar is raised to its highest position, a lateral pin on the vertical depending arm and a pin on the plunger bar adapted to co-act with the last named lateral pin to move the vertical arm outward at the lower end of the stroke of the plunger bar, and an eyelet feeding device removably connected to the lower end of the vertical arm.

In testimony whereof we affix our signatures in presence of two witnesses.

ISADORE COHEN.
ALEXANDER LANDSBERG.
